UNITED STATES PATENT OFFICE

RAY R. HUTCHESON, OF RICHMOND HILL, NEW YORK, ASSIGNOR TO AMERICAN NICOTON CORPORATION, OF NEW YORK, N. Y., A CORPORATION OF NEW YORK

DESIGN FOR A COMBINED LIQUID APPLICATOR AND PAD

Application filed July 20, 1931. Serial No. 40,600. Term of patent 14 years.

To all whom it may concern:

Be it known that I, RAY R. HUTCHESON, a citizen of the United States, residing at Richmond Hill, in the county of Queens and State of New York, have invented a certain new, original, and ornamental Design for Combined Liquid Applicator and Pad, of which the following is a specification, reference being had to the accompanying drawings, forming part thereof.

Fig. 1 is a perspective view of my new design of combined liquid applicator and pad,

showing the top or cover in open position.

Fig. 2 is a fragmentary view similar to Fig. 1 but showing the top in closed position.

When the top is open as shown in Fig. 1, it exposes the underlying pad saturated with the liquid contained within the body of the applicator.

I claim:

The ornamental design for a combined liquid applicator and pad, as shown and described.

RAY R. HUTCHESON.
